UNITED STATES PATENT OFFICE.

ROBERT A. READ, OF TORONTO, ONTARIO, CANADA.

CLOTH-CUTTER GUARD.

1,283,895.

Specification of Letters Patent. Patented Nov. 5, 1918.

Application filed April 3, 1918. Serial No. 226,392.

To all whom it may concern:

Be it known that I, ROBERT A. READ, of the city of Toronto, in the county of York, Province of Ontario, Canada, have invented 5 certain new and useful Improvements in Cloth-Cutter Guards, of which the following is a specification.

This invention relates to cloth cutters employing a vertically reciprocating knife and 10 a presser foot which holds the fabric being cut down against the base on which the machine is supported. In the specific machine of this type illustrated in the accompanying drawings, part of the knife above the presser 15 foot is exposed so that the operator while holding down the fabric in front of the knife is very apt to cut his fingers more or less seriously, and, further, when the edge of a pile of fabric is reached the hand may 20 drop below the presser foot and into the path of the knife, and it is my object to provide an attachment which will effectively 25 guard the knife without interfering in any way with the operation of the machine.

I attain my object by means of the constructions hereinafter described and illustrated in the accompanying drawings in which—

Figure 1 is a side elevation showing part 30 of a cutter provided with my guard; and

Fig. 2 a plan view of the same parts.

In the drawings like numerals of reference indicate corresponding parts in the different figures.

1 is the base of the machine from which 35 extends the standard 2 on which the frame 3 of the device is supported. The knife 4 runs in the standard as shown with its edge projecting. 5 is the presser bar suitably 40 guided in bearings 6 on part of the frame 3. The presser bar and its arrangement form no part of the present invention and may be 45 of any ordinary type.

Secured to the lower part of the presser 50 bar is a clamp 7 and to the upper end is secured a clamp 8. To the lower clamp is secured a bent wire metal guard 9, which extends rearwardly and overlaps the knife on the left hand side thereof when the apparatus 55 is in the position in which it is used. The forward edge of this guard is formed as a rod 10. This rod passes through a hole in the upper clamp 8 and is thus held in position. This gives a suitable support for the guard without interfering in any way with the other parts of the machine. The

guard being supported at the extreme ends of the presser foot, the vertical adjustment of the latter is in no way interfered with. The edge of the knife above the presser foot 60 is thus completely protected at the only side on which it is accessible by the hand of the operator, who frequently finds it necessary to press or hold down the goods just as they pass under the presser foot.

The presser foot is of peculiar construction. A toe 11 is extended forwardly from the presser foot for some considerable distance in a horizontal direction and the end 12 is turned up slightly so that the toe will 65 ride easily over the material being cut. When the presser foot reaches the edge of the pile of fabric being cut, the toe will project over the edge. It is quite common for a cutter to work with his left hand in front of 70 the presser foot with the fingers on the fabric at one side and the thumb on the fabric at the other side of the presser foot holding down the fabric. When the edge of the pile of fabric is reached, unless the 75 operator is alert, his hand may drop and be caught by the knife below the presser foot. The projecting toe prevents this, as the hand will drop on to the toe as soon as the support of the pile of fabric beneath the 80 finger tips is removed, and thus the hand is held up and prevented from contacting with the knife. This projecting toe thus 85 operates with the guard 9 in the prevention 90 of accidents to the operator.

What I claim as my invention is:—

1. The combination with a cloth cutter provided with a frame, a base, a standard connecting the frame and the base, a vertically reciprocating knife, a presser foot, a 95 presser bar to which the presser foot is connected and upper and lower guides for said bar, of a guard comprising an open metal frame located in front and to one side of the knife above the presser foot; and supports 100 for the guard connected to the presser bar above the upper and below the lower guide thereof.

2. The combination with a cloth cutter provided with a frame, a base, a standard 105 connecting the frame and the base, a vertically reciprocating knife, a presser foot, and a suitably guided presser bar to which the presser foot is connected, of a guard located in front and to one side of the knife 110 above the presser foot, a rod extending up from the front side of the guard; a clamp

secured to the lower end of the presser bar to which the lower end of the guard is secured; and a clamp secured to the upper end of the presser bar embracing the upper end 5 of the rod.

3. The combination with a cloth cutter provided with a frame, a base, a standard connecting the frame and the base, a vertically reciprocating knife, a presser foot, and 10 a suitably guided presser bar to which the presser foot is connected and upper and lower guides for said bar, of a guard located in front and to one side of the knife above the presser foot; and supports for the guard 15 extending laterally and connected to the presser bar above the upper and below the lower guide thereof.

4. The combination with a cloth cutter provided with a frame, a base, a standard 20 connecting the frame and the base, a vertically reciprocating knife, a presser foot, and a suitably guided presser bar to which the presser foot is connected, of a guard located in front and to one side of the knife above 25 the presser foot; a rod extending up from the front side of the guard; a laterally extending clamp secured to the lower end of the presser bar to which the lower end of the guard is secured; and a laterally extending 30 clamp secured to the upper end of the presser bar embracing the upper end of the rod.

5. The combination with a cloth cutter provided with a frame, a base, a standard connecting the frame and the base, a vertically reciprocating knife, a presser foot, 35 and a suitably guided presser bar to which the presser foot is connected and upper and lower guides for said bar, of a guard located in front and to one side of the knife above the presser foot having its lower edge 40 inclined downwardly from the front to the rear; and supports for the guard connected to the presser bar above the upper and below the lower guide thereof.

6. The combination with a cloth cutter 45 provided with a frame, a base, a standard connecting the frame and the base, a vertically reciprocating knife, a presser foot formed with a forwardly projecting horizontal toe with upwardly inclined forward 50 end, a suitably guided presser bar to which the presser foot is connected and upper and lower guides for said bar, of a guard located in front and to one side of the knife above the presser foot; and supports for the guard 55 extending laterally and connected to the presser bar above the upper and below the lower guide thereof.

Signed at Toronto, Canada, this 15th day of March, 1918.

ROBERT A. READ.
